(57) **CLAIM**

I claim the ornamental design for a baby pacifier, as shown.

DESCRIPTION

FIG. 1 is a front perspective view of a baby pacifier, showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top view thereof;

FIG. 7 is a bottom view thereof; and,

FIG. 8 is a rear perspective view thereof.

In the drawings, the broken lines depict portions of the baby pacifier that form no part of the claimed design.

1 Claim, 8 Drawing Sheets
